US0D1104608S

(12) **United States Design Patent** (10) **Patent No.:** **US D1,104,608 S**
Wang et al. (45) **Date of Patent:** **** Dec. 9, 2025**

(54) **WARMING PLATE**

(71) Applicant: **Shenzhen Jiachen Plastic Hardware Electronics Co., LTD**, Guangdong (CN)

(72) Inventors: **Meiyan Wang**, Quanzhou Fujian (CN); **Zewei Wang**, Quanzhou Fujian (CN)

(73) Assignee: **Shenzhen Jiachen Plastic Hardware Electronics Co., LTD**, Shenzhen (CN)

(*) Notice: Patent file contains an affidavit/declaration under 37 CFR 1.130(b).

(**) Term: **15 Years**

(21) Appl. No.: **29/979,279**

(22) Filed: **Dec. 18, 2024**

(57) **CLAIM**

The ornamental design for a warming plate, as shown and described.

DESCRIPTION

FIG. 1 is a front perspective view of a warming plate showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the warming plate that form no part of the claimed design.

1 Claim, 8 Drawing Sheets
